(57) **CLAIM**

The ornamental design for a phone organizer as shown and described.

DESCRIPTION

FIG. 1 is a front elevational view of a cover of a phone organizer showing my new design shown separately for ease of illustration;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof;

FIG. 8 is another perspective view thereof;

FIG. 9 is a front elevational view of a phone case of the phone organizer shown separately for ease of illustration;

FIG. 10 is a rear elevational view thereof;

FIG. 11 is a left side elevational view thereof;

FIG. 12 is a right side elevational view thereof;

FIG. 13 is a top plan view thereof;

FIG. 14 is a bottom plan view thereof;

FIG. 15 is a perspective view thereof;

FIG. 16 is another perspective view thereof;

FIG. 17 is a perspective view of the phone organizer where the cover is assembled with the main body;

FIG. 18 is another perspective view thereof;

FIG. 19 is a perspective view of the phone organizer shown in a closed state; and,

FIG. 20 is another perspective view thereof.

The broken lines in the drawings depict portions of the phone organizer that form no part of the claimed design.

1 Claim, 20 Drawing Sheets
